United States Patent Office.

THOMAS T. POWELL AND JOHN F. BURROUGHS, OF LAWN RIDGE, ILLINOIS.

Letters Patent No. 97,808, dated December 14, 1869.

IMPROVED CONVERTIBLE END-BOARD AND PLATFORM FOR WAGONS.

The Schedule referred to in these Letters Patent and making part of the same.

To all whom it may concern:

Be it known that we, THOMAS T. POWELL and JOHN F. BURROUGHS, of Lawn Ridge, in the county of Marshall, and in the State of Illinois, have invented a new and useful Improvement in End-Boards for Wagons and Carts, &c.; and do hereby declare that the following is a full, clear, and exact description thereof, reference being had to the annexed drawings, making a part of this specification, in which like letters of reference refer to like parts, and in which—

Figure 1 represents a perspective view.

Figure 2, perspective view of the gate or end-board opened, with platform or extension of wagon-bottom in place.

Figure 3, plan of gate or end-board, and that portion of wagon.

Figure 4, elevation of end of wagon-gate and platform-stay.

This invention relates to the use of a double gate, in place of the ordinary end-board of a wagon; also, a sliding horizontal platform, or extension of the wagon-bottom, which, together, form a platform and sides, for the convenience of shovelling or unloading produce of various kinds, or articles generally carried in bulk. The seat of the wagon is reversed, and forms the "platform" in question.

A is the wagon-body.

B is a horizontal platform, which is also the seat of the wagon, whose length is of the same width as that of the wagon-bed.

This seat and end-board has a bar, e, fastened to each end, and parallel therewith, projecting several inches beyond the edge which closes with the wagon-end or bed, each fitting into one of the sockets or mortises f, cut in the transverse bar g, under the end of the wagon-bed.

This board has a staple or hook, k k, or equivalent device, for the purpose of securing the ends of the gates C D, when opened, to form sides for the board or platform.

The bars e e, besides forming a support for the end-board, also act as stays or cleats, to keep the board, when used as the wagon-seat, from sliding so as to fall.

C D are two gates, or divisions of the end of the wagon, each hinged vertically at their outer edges to the wagon, and having straps of malleable iron running along their upper and lower edges, and terminating at the joint or union of the meeting-edges of the gates, in eyes d d d d, which receive a vertical bolt or rod, i, which passes through them all into the wagon-bed below, where a socket and thread may receive and secure the thread on the end of the rod.

Vertical braces, a a, are screwed, one on either gate, at such a distance from the hinged edge of each as to make a good abutment against the end of the side-board of the wagon when the gates are opened. (See figs. 2 and 3.)

The meeting edges of the gates may be recessed or lapped, as shown in drawings, so as to secure the small grain, &c., from escaping.

Staples or hooks k k, or equivalent devices, secure the gates (when opened) to the platform B.

The whole forms a strong, compact, and good plan for the unloading of articles carried in bulk, the platform B afterward being replaced as a seat, as shown in fig. 1.

We claim, as our invention—

1. The use and construction of the board B, both as a platform or wagon-bed extension, and as a wagon-seat, with its staples or hooks k k, or equivalent fastenings for the gates, and the bars e e, substantially as described, and for the purposes set forth.

2. In combination with the above, the gates C D, with their straps b b b b and eyes d d d d, secured by the rod i and auxiliary recess l, the braces a a, and the transverse bar g, with its recesses or mortises f f, all substantially as described, and for the purposes hereinabove stated.

In testimony that we claim the foregoing, we have hereunto set our hands, this 29th day of September, 1869.

THOMAS T. POWELL.
JOHN F. BURROUGHS.
